UNITED STATES PATENT OFFICE.

WILLIAM T. BIRD, OF SHEFFIELD, IOWA, ASSIGNOR OF ONE-HALF TO J. S. WARTNABY,
OF SHEFFIELD, IOWA.

WIRE-GATE FASTENER.

1,042,757.

Specification of Letters Patent.

Patented Oct. 29, 1912.

Application filed December 7, 1911. Serial No. 664,482.

To all whom it may concern:

Be it known that I, WILLIAM T. BIRD, citizen of the United States of America, and resident of Sheffield, Franklin county, Iowa, have invented a new and useful Wire-Gate Fastener, of which the following is a specification.

The object of this invention is to provide an improved construction for fastening and stretching means for wire gates.

My invention consists in the construction, arrangement and combination of elements hereinafter set forth, pointed out in my claims and illustrated by the accompanying drawing, in which—

Figure 1 is an elevation showing the gate fastening in open or inoperative position. Fig. 2 is an elevation like unto Fig. 1 showing the gate fastener in operative or closed position. Fig. 3 is a vertical section on the indicated line 3—3 of Fig. 2.

In the construction of the device as shown the numeral 10 designates a stretcher or evener bar adapted to be secured to end portions of gate wires such as 11. The gate wires 11 may be independent sections secured at their opposite ends to a post (not shown) or they may form continuations of the strand wires of a fence in a common and well known manner and they may be of any desired number. The gate wires 11 preferably extend through horizontal holes in the stretcher or evener bar 10 and are secured rigidly yet removably thereto. The evener bar 10 also is formed with a plurality of slots 12, in this instance two in number, and hooks 13, 14, preferably made of metal, are mounted with their stems extending through said slots and slidably engaging therein. Movement of the stems of the hooks 13, 14 through the slots 12 is limited in one direction by pins 15 mounted in the extremities of said stems. The hooks 13, 14 are adapted to engage at times with

a post 16 and to that end are of such size and shape and can be bent and adjusted to fit such post in embracing relations. A stay bar 17 is mounted on and connects the hooks 13, 14 parallel with and in front of the stretcher or evener bar 10. A curved lever 18 is fulcrumed intermediate of its ends on the central portion of the stay bar 17. One end portion of the lever 18 is forked and carries a bolt 19 extending across its fork.

A draw rod 20, curved at its forward end, 55 is pivoted at its extremity to the bolt 19 and is pivotally connected at its rear end to an eye-bolt 21, which eye-bolt extends horizontally through the central portion of the stretcher or evener bar 10 approximately 60 midway between the hooks 13, 14. The lever 18 may be provided if desired with a handle 22 on the extremity of its long arm. The curvature of one end portion of the draw rod 20 corresponds to the curvature of the 65 short arm of the lever 18 and said curved portion of the rod is adapted to lie at times in contact with the convex face of said short arm.

In practical use the parts are assembled 70 as shown in Fig. 1, the hooks 13, 14 being detached from the post 16. In such position and condition of parts the gate and fastening device may be moved through an arc in either direction to open a driveway or pas- 75 sageway. To close the gate the parts in the positions shown in Fig. 1 are moved horizontally until the hooks 13, 14 engage the post 16 and then the lever is turned on its fulcrum, the handle 22 being moved man- 80 ually downwardly through an arc until the parts are brought into the positions shown in Fig. 2. Movement of the lever 18 as de- 85 scribed applies draft through the rod 20 upon the stretcher or evener bar 10 to the end of moving said stretcher or evener bar toward the post 16 and applying desired strain and tightening effect to the wires 11. The movement of the lever 18 is continued until the bolt 19 is moved across a line in- 90 tersecting the center of the fulcrum and the axis of articulation of the rod 20 on the eye-bolt 21, at which time the lever is retained in position by strain on said rod. A reverse movement of the lever will slacken the parts 95 to such extent that the hooks 13, 14 may be removed from the post 16 manually to open the gate.

I claim as my invention—

1. A wire-gate fastener, comprising hooks, 100 a stay bar connecting said hooks, a stretcher slidably mounted on said hooks, a lever fulcrumed on said stay bar, a rod connecting said lever and stretcher, and means for securing gate elements to said stretcher. 105

2. A wire-gate fastener, comprising a stretcher formed with slots, means for securing gate elements to said stretcher, hooks

slidingly mounted in said slots, a stay bar on said hooks, a lever fulcrumed on said stay bar, and a draw rod pivotally connecting one end of said lever to said stretcher.

5. 3. A wire-gate fastener, comprising a stretcher formed with slots, means for securing gate elements to said stretcher, hooks slidingly mounted in said slots, a stay bar on said hooks, a lever fulcrumed on said stay bar, and a draw rod pivotally connecting one end of said lever to said stretcher, adjacent end portions of said lever and draw rod being curved concentrically.

10 4. A wire-gate fastener, comprising a stretcher formed with slots, means for securing gate elements to said stretcher, hooks slidingly mounted in said slots, pins mounted in extremities of said hooks, a stay bar on said hooks, a lever fulcrumed on said stay

bar, and a draw rod pivotally connecting 20 one end of said lever to said stretcher.

5. A wire-gate fastener, comprising a stretcher formed with slots, means for securing gate elements to said stretcher, hooks slidingly mounted in said slots, pins mounted 25 in extremities of said hooks, a stay bar on said hooks, a lever fulcrumed on said stay bar, and a draw rod pivotally connecting one end of said lever to said stretcher, adjacent end portions of said lever and draw rod 30 being curved concentrically.

Signed by me at Sheffield, Iowa, this 24th day of August, 1911.

WILLIAM T. BIRD.
